UNITED STATES PATENT OFFICE

LEON FRIEDMAN, OF MILWAUKEE, WISCONSIN

NECKTIE

Application filed October 8, 1928. Serial No. 311,136.

This invention relates to neckties.

In neckties of the better variety it has been found that where the necktie is lined with a silk lining throughout its extent, it sells considerably better than otherwise. However, it has been found that the silk lining and the main body or covering of the tie, do not stretch to the same degree and puckering results after a short interval of use.

10 This invention is designed to overcome the defects noted above, and objects of this invention are to provide a novel necktie which is so constructed that the lining, which preferably extends from one end of the tie to the other, adheres throughout its extent to the cover or outer portion of the tie, so that when stretching occurs, the two layers will move as one unit and independent, or irregular stretching of the layers will not result 15 with the consequence that the tie will remain smooth and substantially free from wrinkles for a great length of time.

20 More specifically, objects of this invention are to provide a novel form of necktie, in which the lining is provided with a silk outer exposed face and with a wool interior, which give body to the tie, and which also provides a nap which interlocks or engages the entire face of the outer covering of the tie, and thus causes the lining to adhere throughout its 25 length to the outer covering of the tie.

25 Further objects of this invention are to provide a novel form of tie in which the lining, as well as the outer ply, is woven upon a bias, so that the outer ply and lining fabric may be laid one upon the other and the patterns placed thereon and the tie cut therefrom thus simultaneously cutting both the lining and the outer ply. Thereafter, the 30 edges are sewed together, as will hereinafter be described, and the angle of the warp and weft lining is identically the same as the warp and weft of the outer ply. This insures the uniform stretching or motion of the lining and the outer ply, so that these two members move as a unit due to the fact that their threads run in identically the same manner.

An embodiment of the invention is shown in the accompanying drawings in which:

50 Figure 1 is a view from the inner side of

the necktie, laid out flat before it is folded;

Figure 2 is a similar view showing the tie in its folded condition;

Figure 3 is an enlarged fragmentary section on the line 3—3 of Figure 1.

Referring to the drawings, it will be seen that the necktie comprises an outer covering 1, which is usually of silk, or high grade material. The inner lining 2 has a silk outer face and has a wool inner face 3 which is formed with a decided nap. These layers, that is to say, the outer covering and the inner lining, are stitched together by lines of stitching 4 throughout the major portion of their extent while the two layers are reversed. Thereafter, the tie is turned inside out and additional stitching 5 is formed at its ends to close the ends of the tie.

With the tie constructed in this manner, it has been found from actual tests that the two layers 1 and 2 stretch as a single unit, as the inner layer substantially adheres to the outer layer throughout its entire extent. There is, therefore, no necessity for other stiffening or body-giving material than the inner lining, its inner lining being formed with a wool interior and a silk exterior which gives a sufficient body to the tie to answer all of the requirements.

The lining is woven on a bias, as well as the outer covering. This enables the material for the lining as well as the outer covering to be laid one upon the other and the patterns then laid on the two pieces so that both the lining and the outer covering can be cut at the same time. Thereafter, the plies are stitched together, as described above, and it will be seen that the angle of the threads is identically the same in both the lining and the outer ply. As shown, for instance, in Figures 1 and 2, the angle of the threads is the same in the outer ply and at the lining, as indicated at the portions 6 and 7.

Thus, the stretching or give of the outer ply and of the lining is identically the same, so that there is no puckering.

In addition, the tie has the novel characteristics noted above in that it will stretch as a single unit and not as two composite layers when in actual use.

Although the invention has been described in considerable detail, such description is intended as illustrative rather than limiting as the invention may be variously embodied and 5 as the scope of such invention is to be determined as claimed.

I claim:—

A necktie comprising an outer covering and an inner lining, the inner lining having 10 a silk outer side and a wool inner side having a decided nap, with the nap in contact with the covering, the warp and weft threads of the lining and covering running at a bias and at identically the same angle whereby to provide 15 for the same degree of simultaneous give in the lining and outer covering.

In testimony that I claim the foregoing I have hereunto set my hand at Milwaukee, in the county of Milwaukee and State of Wisconsin.

LEON FRIEDMAN.
